UNITED STATES PATENT OFFICE.

JOSÉ DEL MORAL, OF EAST ORANGE, NEW JERSEY.

ROTARY STEAM ENGINE.

Application filed October 2, 1920. Serial No. 414,129.

To all whom it may concern:

Be it known that I, JOSÉ DEL MORAL, a citizen of Mexico, residing at Ampere, East Orange, in the county of Essex and State 5 of New Jersey, have invented new and useful Improvements in Rotary Steam Engines, of which the following is a specification.

This invention relates to steam engines, 10 and comprehends the construction designed to utilize the absolute pressure of the steam without using a condenser. While the invention is shown and described in connection with a rotary engine, I desire to have 15 it understood that the invention may be embodied in other types of engines.

In carrying out the invention I provide an injector for conveying steam from the boiler to the rotor chamber and to return 20 the exhausted steam from said chamber to the injector in a manner so that the exhaust steam is brought into contact with the steam from the boiler, whereby the energies of both are combined prior to the admittance 25 of the steam to the rotor chamber.

One of the chief characteristics of the invention resides in providing an injector of novel construction, whereby its area can be readily and easily adjusted.

30 A further object of the invention resides in the provision of means to automatically regulate the area of the injector during the various loads at which the engine is working.

It is also my purpose to provide the rotor 35 of the engine with a plurality of sliding pistons, which are designed to be maintained in effective contact with the wall of the chamber by the pressure within the latter.

The nature and advantages of the invention will be better understood when the following detailed description is read in connection with the accompanying drawings, the invention residing in the construction, combination and arrangement of parts as 45 claimed.

In the drawings forming part of this application like numerals of reference indicate similar parts in the several views and wherein:

50 Figure 1 is a side elevation of the engine constructed in accordance with the invention.

Figure 2 is a sectional view on line 2-2 of Figure 1.

55 Figure 3 is an enlarged vertical sectional view through the engine.

Figure 4 is an enlarged sectional view taken at right angles to Figure 3.

Figure 5 is a sectional view on an enlarged scale of the combining or mixing chamber 60 including the principal elements of what I term the combining or mixing apparatus or injector.

Figure 6 is a sectional view on an enlarged scale; taken through one of the sliding pistons. 65

Referring to the drawings in detail 10 indicates the base upon which the engine casing is mounted, this casing being connected at 11 and formed to provide a chamber 12 70 for the rotor 13. The casing 11 is provided with an inlet port 14 tangentially disposed beneath the rotor and an exhaust or outlet port 15 tangentially disposed above the rotor, both of these ports opening at the same 75 side of the casing 11. The rotor 13 is formed with radially disposed slots 16 in each of which is arranged a sliding piston 17. Each piston is made in two sections as clearly illustrated with the respective sections formed with longitudinally extending bores 18 which open at one side of the section to admit fluid within the rotor chamber, the fluid operating against the lower ends 80 of the piston sections to force the latter outwardly into effective contact with the wall of the rotor chamber. The rotor 13 is supported between the disks 19 which are carried by the shaft 20, the disks being secured to the opposed sides of the rotor in any suitable manner. Casings 21 are arranged about the disks 19 and cover the eccentricity between the disks and the casing 11, the casings 21 being held tight against the sides 85 of the pistons by means of springs 22 which provide a fluid tight connection between the said casings and pistons. Arranged at one side of the casing 11 is an oil reservoir 23 from which oil flows through a bore 24 into the shaft 20 and thence radially through 90 bores 25 in the disks 19. The oil spray is thrown up by centrifugal action of the rotor and covers the pistons and ring 26 and provides effective lubrication about moving parts of the engine. 95

100 Mounted upon the base 10 to one side of the casing 11 is the combining mixing chamber forming part of the injector and including a hollow tubular body portion 27 which is disposed in axial alignment with the inlet port 14 of the casing 11 and secured thereto by means of suitable fastening elements 28. 105

Received by the tubular body portion 27 of the mixing chamber is one end of a conduit 29, the opposite end extending upwardly terminating to provide a semi-spherical portion 30 which is secured to a similar portion 31 of an exhaust pipe 32 which is bolted to the casing 11 about the exhaust port 15. The pipe 32 projects below the meeting edges of the semi-spherical portions 30 and 10 31 respectively terminating in close proximity to the upper end of the pipe 29. The space and valve seat have a valve 33 fitted upon the adjacent end of the exhaust pipe 32. This valve controls escape of the exhaust from the pipe 32 through the port 34. Arranged within the pipe 29 is a plurality of spaced curved partitions 35 which define passages 36 through which the exhaust from the pipe 32 enters the mixing 20 chamber 27. These partitions extend an appreciable distance within the chamber 27 as shown. The central partition 35 has that portion disposed within the mixing chamber 27 formed to provide a steam chest 25 or receiver whose upper and lower walls after meeting to form a narrow section or throat 36 spread out in a divergent flare to define a nozzle 37 of the well known expanding form which guides and directs the 30 motion of the actuating jet 36'. Intermediate this steam chest is a supply pipe 38 which conveys steam from the boiler 39 to the steam chest or receiver. Arranged above and below the expanding nozzles are what I 35 term mixing blades 40, these blades having their corresponding extremities pivoted as at 41 to the adjacent partitions 35. These mixing blades slightly converge toward the discharge end of the mixing chamber 27. 40 Arranged above and below the blades 40 are relatively long blades 42 which will be hereinafter known as delivery blades, the latter having their corresponding extremities pivoted as at 43 to the adjacent end of the pipe 45 45 and also disposed in convergent relation and spaced from the blades 40. As above stated, the delivery blades 42 are considerably longer than the mixing blades 40 and project beyond the chamber 27 terminating an appreciable distance within the 50 inlet bore of the casing 11.

In practice, steam at high pressure is conveyed from the boiler 39 through the pipe 38 into the steam chest passing through the 55 expanding nozzle into the space between the mixing blades 40. The steam thus expanded has its volume and velocity greatly increased, its pressure energy being converted into energy of velocity. The steam then passes 60 between the mixing blades 40 and forcibly strikes against the converging delivery blades 42 and is thereby reduced in volume and velocity, or in other words the condition previously existing merely reversed, 65 that is, this energy of velocity acquired

while passing through the expanding nozzle being converted into pressure energy, so that upon passing between the restricted space between the free ends of the delivery blades 42 into the casing 11, the steam urging the pistons forward as it recovers its primitive potential energy or high pressure. The steam passing through the expanding nozzle and the mixing chamber 27 in the manner just described creates a suction in 70 the exhaust pipe 32 which lowers the pressure therein and momentarily closes the valve 33, thus prohibiting the exhaust passing through the pipe 32 to escape through the member 40, which exhaust is consequently 75 drawn into the mixing chamber 27 passing through the space between the partitions 35 in thin sheets or streams at both sides of the discharge opening of the expanding nozzle. When the exhaust enters the mixing 80 chamber in this manner, it mingles with the steam from the boiler, so that the energies of both are combined prior to the entrance of fluid into the rotor chamber 11. Both the steam from the boiler and the exhaust 85 from the rotor chamber are thoroughly mixed within the chamber by the construction shown, and both fluids move along together with a common velocity and increase momentum sufficient to force the combined masses of the two fluids through the restricted passage between the free extremities of the delivery blades 42, and thereby overcome the high pressure in the chamber 14. The fluid admitted to the chamber 100 14 obviously strikes against the sliding pistons to forcibly rotate the rotor, a portion of the fluid entering the bores provided in the piston sections to hold the latter effectively in contact with the wall of the rotor chamber as above described. 105

If the area of the discharge end of the delivery blades 42 were fixed at a given size, it would be too large when the steam supply from the boiler is reduced, and evidently too small when augmented, to permit sufficient passage for the increase of the mixture; consequently pressure would be raised at the exhaust and the steam wasted thereof. It is therefore my purpose to provide means to automatically regulate the area of the discharge end of the delivery blades 42 to compensate for any change in conditions. In carrying this idea into effect I provide a cylinder 45 at each side 110 of the mixing chamber 27 and establish communication between these cylinders and the exhaust pipe 32 by means of branch pipes 46 terminally connected with the cylinder 45 and communicating at a point above the mixing chamber 27 with a main pipe 47 which has one end suitably secured to the exhaust pipe 32 at a point immediately above the valve 33. Arranged for reciprocatory movement within each cylinder 45 is a piston 48 115 120 125 130

having associated therewith a piston rod 49 which carries a cross piece 50 at the outer end thereof. Pivots connected with this cross piece 50 are the corresponding extremities of links 51, the opposite ends of which are pivotally connected to the arms 52 arranged parallel to each other above and below the cylinder 45. These arms are connected with the delivery blades 42 at their point of pivotal connection 43 as shown. Consequently the delivery blades 42 are automatically adjusted to compensate for any change in conditions, the blades being controlled by the arms 52 which in turn are actuated by the main piston 48 which floating between two balancing pressures, namely the atmosphere and internal pressure will readily respond to any change in conditions and automatically regulate the size of the discharge end between the delivery blades 42 during the various loads at which the engine is working. The valve 33 operates simultaneously for the reason that the area of the exhaust opening must allow, at any given load, free exit for the volume of steam admitted into the engine at the pressure of the boiler, which steam is expanded down to the pressure of the atmosphere during its transit through the exhaust pipe 32 through the mixing chamber 27. By reason of the construction and operation described, it is manifest that the engine will be enabled to utilize the absolute pressure developed by the steam in the boiler without the use of a condenser, and as there can be no escape of steam throughout through the exhaust pipe 32 which returns the exhaust to the mixing chamber 27, the construction provides for both a very efficient and economic engine.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim is:

1. In an engine of the class described, a chamber having an inlet port and an exhaust port, a rotor operating within said chamber, a combining mixing apparatus or injector associated with said inlet port, a fluid supply pipe communicating with said injector, means for conveying the exhaust from the engine to said mixing chamber for further use, and relatively movable mixing blades arranged within the chamber and at opposite side of said steam nozzle.

2. In an engine of the class described, a chamber having an inlet port and an exhaust port, a rotor operating within the chamber, a combining mixing apparatus or injector associated with said inlet port, a fluid supply pipe communicating with said injector,

means for conveying the exhaust from the engine to the mixing apparatus in sheets about the divergent nozzle, and relatively movable mixing blades arranged within the mixing chamber above and below said nozzle and convergently disposed. 70

3. In an engine of the class described, a chamber having an inlet port and an exhaust port, a rotor operating within the chamber, a combining or mixing apparatus 75 or injector associated with said inlet port, a fluid supply pipe communicating with said inlet port, a fluid supply pipe communicating with said injector, means for conveying the exhaust from the engine to the mixing chamber for further use, means for mixing the exhaust with the fluid from said supply prior to its introduction into said inlet port, and relatively movable delivery blades forming part of the mixing chamber and projecting within said inlet port of the engine. 80

4. In an engine of the class described, a chamber having an inlet port and an exhaust port, a rotor operating within said chamber, a combining or mixing apparatus or injector 90 associated with said inlet port, means for conveying fluid from a source of supply to said injector, means for conveying the exhaust from the engine to the mixing chamber for further use, means whereby said exhaust 95 is conveyed to the mixing chamber in the form of sheets about said expanding nozzle, means whereby the exhaust is mixed with the fluid from said supply prior to its introduction into the inlet port, and relatively movable delivery blades projecting from said mixing chamber into said inlet port and convergently disposed for the purpose specified. 100

5. In an engine of the class described, a chamber having an inlet port and an exhaust port, a rotor operating within said chamber, a combining or mixing chamber or injector associated with said inlet port, means for conveying fluid from a source of supply to said injector, means for conveying the exhaust from the engine to said mixing chamber, means for mixing the exhaust with the fluid from said supply prior to its introduction into said inlet port, relatively movable delivery blades projecting from the mixing chamber into said inlet port in convergent relation, and means for automatically adjusting these blades for the purpose specified. 115

6. In an engine of the class described, a chamber having an inlet port and an exhaust port, a rotor operating within the chamber, a combining or mixing apparatus or injector associated with said inlet port, means for conveying fluid from a source of supply to said injector, a conduit arranged to convey the exhaust from the engine to said mixing chamber, means for mixing the exhaust with the fluid from said supply prior to its intro- 125

duction into the inlet port, relatively movable delivery blades projecting from the mixing chamber into the inlet port for convergent relation, and means controlled by 5 the pressure in said conduit for automatically adjusting said blades for the purpose specified.

7. In an engine of the class described, a chamber having an inlet port and an exhaust port, a rotor operating within said chamber, a combining or mixing apparatus or injector associated with said inlet port, means for conveying fluid from a source of supply to said injector, a conduit arranged to convey 10 the exhaust from the engine to the mixing chamber, means for mixing the exhaust with the fluid from said source of supply prior to its introduction into said inlet port, said conduit having communication with the atmosphere, an automatically operated valve 15 controlling said communication, relatively movable delivery blades projecting from the mixing chamber into said inlet port in convergent relation, and means controlled by 20 the pressure of said conduit for automatically adjusting said blades for the purpose specified.

8. In an engine of the class described, a chamber having an inlet port and an exhaust port, a rotor operating within said chamber, a combining or mixing chamber or injector associated with said inlet port, means for conveying fluid from a source of supply to said injector, means for conveying 25 the exhaust from the engine to said mixing apparatus or injector, means whereby said exhaust is delivered to the mixing chamber in the form of sheets at opposite sides of said nozzle, relatively movable mixing 30 blades arranged within the chamber at opposite sides of the expanding nozzle, and relatively movable delivery blades projecting from the mixing chamber into the inlet port in convergent relation, said delivery 35 blades being disposed relatively to the mixing blades to assist the latter in mixing the

exhaust with the fluid from said source of supply prior to the introduction into the inlet port.

9. In an engine of the class described, a 50 chamber having an inlet port and an exhaust port, a rotor eccentrically mounted within said chamber, and including a plurality of sliding pistons, means for holding the pistons in contact with the wall of said chamber, yieldably supported members arranged at the opposite sides of the pistons above said rotor, a combining or mixing apparatus or injector associated with said inlet port, a fluid supply pipe communicating with said 55 injector, means for conveying the exhaust from the engine to the mixing chamber for further use and means for mixing the exhaust with the fluid from said source of supply prior to its introduction into said inlet 60 pipe port.

10. In an engine of the class described, a chamber having an inlet port and an exhaust port, a rotor eccentrically mounted within said chamber and including a plurality of 70 sliding pistons, these pistons establishing communication with the exhaust port of said chamber after suitable expansion is obtained through the eccentricity, a combined mixing apparatus or injector associated with the exhaust port of said chamber, means for conveying fluid from a source of supply apparatus, means whereby the pressure energy of the fluid conveyed to said apparatus is transformed into energy of velocity prior to 75 its association with the exhaust fluid, means whereby the exhaust of the engine is brought into contact with the motive fluid conveyed to said apparatus from said source of supply, means for mixing said exhaust with 80 the fluid from said source of supply and means whereby the velocity energy of the mixture is transformed into pressure energy prior to its introduction into the inlet port of the engine.

In testimony whereof I affix my signature.
JOSE DEL MORAL.
